UNITED STATES PATENT OFFICE.

WILLIAM H. MINIER, OF TOLEDO, OHIO, ASSIGNOR TO THE K-M MANUFACTURING COMPANY, OF TOLEDO, OHIO, A CORPORATION OF OHIO.

DESIGN FOR A WINDSHIELD-WIPER.

56,762.

Specification for Design.

Patented Dec. 14, 1920.

Application filed August 2, 1920. Serial No. 400,875. Term of patent 14 years.

To all whom it may concern:

Be it known that I, WILLIAM H. MINIER, a citizen of the United States, residing at Toledo, in the county of Lucas and State of Ohio, have invented a new, original, and ornamental Design for Windshield-Wipers, of which the following is a specification, reference being had to the accompanying drawing, forming a part thereof.

Figure 1 is a side view of the wind shield wiper, and Fig. 2 is an end view thereof.

I claim:

The ornamental design for a windshield wiper as shown.

WILLIAM H. MINIER.
